DICE TABLE

Frederick A. Hurley, 1204 Ali Baba Ave.,
Opa Locka, Fla. 33054

Filed Aug. 4, 1970, Ser. No. 24,302

Term of patent 14 years

Int. Cl. D21—01

U.S. Cl. D34—5

The figure on the drawing is a perspective view of a dice table embodying my new design, the side and end opposite to the side and end shown in the drawing presenting an appearance similar to that shown.

I claim:

The ornamental design for a dice table, as shown and described.
